UNITED STATES PATENT OFFICE.

EDWIN L. POWELL, OF WASHINGTON, DISTRICT OF COLUMBIA, ASSIGNOR TO WIRED RADIO, INC., OF NEW YORK, N. Y., A CORPORATION OF DELAWARE.

SIGNAL-RECEIVING CIRCUITS.

Application filed March 6, 1926. Serial No. 92,893.

My invention relates broadly to signal receiving circuits and more particularly to electron tube circuits having means for controlling the degree of feedback between the plate and grid circuits of an autodyne tube.

One of the objects of my invention is to provide a system for automatically stabilizing autodyne tube circuits in signal receiving systems to prevent powerful signals or static impulses from throwing the circuit previously adjusted to peak regeneration, into the condition of self-oscillation.

Another object of my invention is to provide an automatic governor system for electron tube circuits of the autodyne type for keeping the regenerative feedback at a predetermined constant value through the range of the grid circuit tuning means regardless of the variations in the grid circuit resistance resultant from such tuning.

Still another object of my invention is to provide an electron tube system of the autodyne type in which the feedback between the plate and grid circuits can be adjusted to the desired degree of regeneration or self-oscillation with a minimum of reaction of the regenerative control variation on the resonant frequency of the tuned grid circuit.

A further object of my invention is to provide a differential regenerative circuit for signal receiving systems where a balance between two opposing magnetic fields is established in the output circuit of the autodyne tube system for any definite degree of feedback, whereby the system may be automatically maintained in the desired condition.

A still further object of my invention is to provide an electron tube circuit arrangement for receiving systems where the output circuit of the autodyne tube is provided with dual means for both regenerating and degenerating with respect to the grid circuit; and whereby, with a single non-reactive control, a balance may be secured between the two means for any desired resultant degree of regeneration, said balance

being automatically maintained independent of variations in the inherent resistance 50 or the voltage applied to the grid circuit.

Other and further objects of my invention will be understood from the following specification by reference to the accompanying drawings, wherein:

Figure 1 is a diagrammatic view showing an electron tube circuit arranged in accordance with my invention wherein a non-inductive potentiometer is employed for the regeneration control means; Fig. 2 shows a 60 similar arrangement in which the radio frequency and direct current paths to the plate are in parallel; Figs. 3 and 4 show other forms of series and parallel feed systems utilizing capacity control for regeneration 65 in accordance with my invention; and Figs. 5 and 6 show series and parallel feed systems employing the variable coupling type of regenerative control for electron tube circuits constructed in accordance with my invention.

In electron tube amplification or rectification circuits used in signal receiving systems of damped or modulated continuous waves, greatest sensitivity to weak or distant signals is had when the regeneration is increased to the peak value, or just before self-oscillations begin. Likewise, in the reception of continuous wave telegraph signals by the autodyne method, which consists of 75 oscillating the detector at a frequency slightly off resonance from the desired signal so that an audible beat frequency is produced, greatest sensitivity is secured when the local oscillations are the weakest. In either 80 case, the circuits are most critical when so adjusted and their sensitivity is subject to considerable variation, if not to complete loss of reception by reason of the circuit going over from the regenerating to the oscillating condition or vice versa, either as a result of powerful applied signal or static voltages or merely as a result of the variation in grid circuit losses which occur in tuning. Thus, in the normal circuits previously known to the art, it has been neces-

sary to re-adjust the regeneration control device for each particular signal and to follow up the tuning controls when hunting by constant adjustment of the feedback means. The ordinary regenerative tickler may be said to feed negative resistance to its associated grid input circuit which, when built up to the degree where the inherent resistance of the grid circuit is neutralized, will sustain self-oscillations. If the coupling of the tickler to the grid circuit inductance be reversed, degeneration results; that is, the resultant effect is equivalent to an increase in the resistance of the grid circuit. In my invention I provide a degenerating tickler coil to increase the grid circuit resistance appreciably above its inherent value and then supply a regenerative tickler capable of supplying sufficient negative resistance to neutralize the combined effect of the two. I further provide a single means of controlling the magnetic fields set up by the two tickler coils whereby the strength of one is increased as that of the other is decreased, so that the resultant effective field may be adjusted to produce any degree of regeneration or oscillation desired. Then, by reason of its differential action, any variation in the grid circuit causes a corresponding change in both phases of the plate feedback circuit, providing a governor effect which stabilizes the system in the condition adjusted. Thus, once adjusted to peak regeneration or minimum oscillation as desired, my circuit remains always in the most sensitive condition and the regeneration control device requires no further attention regardless of the strength of received impulses or manipulation of the capacity of the grid circuit tuning condenser. My circuit arrangement is both applicable to amplification and rectification, and in order to explain one of its preferred embodiments I have illustrated several methods of operating an electron tube rectification system in accordance with the principles of my invention.

Referring to the drawings in more detail, I have shown in Fig. 1 a resistance controlled circuit with series feed connection to the plate. Reference character 1 designates the grid inductance and 2 the variable condenser which constitute the tuned input circuit to the electron tube detector 4 and which may be energized by a radio antenna system, wired radio conductor, radio frequency amplifier coupling coil or the like. 3 is a stopping condenser in the grid lead to the tube 4, shunted by grid leak 3a. The filament of tube 4 is heated by the battery 10, the current being controlled by the rheostat 21. 5 is the dual tickler coil, which is wound in fixed relation to the grid inductance and has somewhat more than twice the number of turns normally required to

produce oscillations through the frequency range of the grid circuit, a tap 14 near the center of the winding connecting to the plate of the electron tube 4, and the outside ends of the inductance connected across the resistance of the non-inductive potentiometer 6. The sliding contact 15 of the potentiometer completes the plate circuit through the telephone 7 (or audio frequency transformer primary) and high potential battery 8, to the filament, both of which are by-passed for radio frequency current by the condenser 9. In operation, the plate current flows through a divided circuit from the plate of the tube to the slider 15 of the potentiometer 6 and creates two magnetic fields of opposite phase, one of which regenerates while the other degenerates; the strength of the field of one phase varying inversely to that of the opposite phase as the potentiometer slider 15 is moved from one end of the resistance to the other. Once adjusted for a desired degree of feedback, the ratio of the two fields will remain practically constant regardless of fluctuations in the total plate current, whether caused by variations either in circuit losses, or applied grid voltage (signal energy). Thus the potentiometer adjustment for peak regeneration or minimum oscillation, once made for any given setting of the grid circuit tuning condenser, will be constant for all settings of the tuning condenser and the complete system will remain stable regardless of the strength of signals to which it is made resonant. The fixed coupling feature between plate and grid inductances with separate regeneration control means, which gives a constant mutual inductance between the two circuits and, therefore, eliminates considerable of the reaction on circuit frequency which was experienced previously in circuits employing variable coupling for regeneration adjustment, is covered by my co-pending application Serial No. 643,993, for high frequency electrical circuits, filed June 7, 1923. This reaction of the regeneration control adjustment on the grid circuit frequency is still further reduced by my present invention since the total plate circuit impedance for a given frequency, remains essentially constant throughout the useful range of the potentiometer.

Various arrangements are shown in the remaining figures, like reference numerals being used throughout for corresponding parts. Fig. 2 also shows a resistance control but in this arrangement the direct and audio frequency currents are fed to the plate through a radio frequency choke 11, a parallel feed for the radio frequency current being employed. Figs. 3 and 4 show series and parallel feed systems respectively using capacitive control of regeneration, where in a variable condenser 12 having two sets

of stator plates 16 and 17 operates in conjunction with one rotor system 18 to increase the capacitive reactance in one leg of the tickler system as it is decreased in the other. Figs. 5 and 6 represent series and parallel feed systems respectively, but in these two cases the control is by variable coupling at 18, under which condition two oppositely wound tickler coils 19 and 20 set 10 90 degrees to each other and connected in parallel are arranged to permit rotation through an angle of 90 degrees with respect to the grid inductance 1, thereby increasing the regenerative feedback as degeneration 15 diminishes and vice versa.

In practical operation of my invention, I have carefully investigated the merits of the balance winding system with the degenerating winding open and closed. With the 20 degenerating winding open, oscillations were obtained when the tuning condenser was set at maximum with regeneration control at 10 degrees, but when the condenser was reduced to the minimum setting, 60 degrees 25 of the regeneration control was required, the gradation for intermediate values being fairly constant between the two limits. With the balance winding connected in, oscillations were obtained at 70 degrees of regeneration throughout the range of the tuning condenser. Set to peak regeneration with no applied signal, no oscillations were developed when the local station was tuned in. Without the balancing winding and 30 with the receiver located at Washington, D. C., station KFI in California could not be received because of strong static discharges setting the circuit into oscillation, but with the differential system operating 35 fair audibility was obtained. The reaction for the total oscillating range of the potentiometer (50 degrees) on KDKA's (East Pittsburgh, Pa.) wave was about 3 kcs. without the reversed tickler, but with the 40 differential system operating, 30 degrees variation of the control reduced this frequency shift to the order of 0.4 kcs.

While I have described my invention in certain preferred embodiments, I desire that 50 it be understood that modifications may be made and that no limitations upon the invention are intended other than those imposed by the scope of the appended claims.

What I claim and desire to secure by Letters Patent of the United States is as follows:

1. An electron tube system comprising in combination with an electron tube having grid, filament and plate electrodes, an input 55 circuit including said grid and filament electrodes, an output circuit including said plate and filament electrodes, and a differential circuit interlinking said input and output circuits comprising an inductance 60 shunted by an impedance, said impedance

becoming increasingly large in one portion of said differential circuit while said impedance decreases in another portion of said differential circuit, one portion of said differential circuit operating to facilitate regeneration in said circuits, and another portion of said differential circuit operating to reduce the tendency of said circuits to regenerate, whereby a balanced condition of operation of said circuits may be maintained in a predetermined state of regeneration or oscillation. 70

2. An electron tube system comprising in combination with an electron tube having grid, filament and plate electrodes, an input 80 circuit including said grid and filament electrodes, an output circuit including said plate and filament electrodes, an inductance located in each of said circuits, the inductance in said output circuit having a midpoint thereof connected with said plate electrode, a resistance shunted across said last named inductance and having a variable connection extending between said resistance and said output circuit, whereby the state of regeneration or oscillation in said circuits may be manually adjusted and automatically maintained. 85

3. In an electron tube system the combination with an electron tube having grid, filament and plate electrodes, input and output circuits interconnecting said electrodes, a balance circuit including an inductance device shunted by a resistance, a connection between the midpoint of said inductance and said plate electrode, said inductance and resistance, being interposed in said output circuit and being related to said input circuit in such manner that said circuit tends to govern the regenerative properties of 95 said electron tube system and maintain said electron tube system in a substantially constant condition of regeneration or oscillation. 100

4. In an electron tube system, the combination of an electron tube having grid, filament and plate electrodes, input and output circuits interconnecting said electrodes, a balance circuit connected in said output circuit, said balance circuit having one point thereof connected to said plate electrode and having means connected across the opposite ends thereof and variably associated with a point in said output circuit for governing 110 the regenerative action of said electron tube circuits. 115

5. In an electron tube system the combination of an electron tube having grid, filament and plate electrodes, input and output circuits interconnecting said electrodes, an inductance device included in each of said circuits, the inductance device in said output circuit being connected in a balance circuit with a connection between a midpoint 125 of said last mentioned inductance device 130

4
and said plate electrode, and means connected across said balance circuit for variably increasing or decreasing the regenerative properties of said electron tube circuits, said balance circuit maintaining said electron tube circuits in a predetermined constant state of regeneration or oscillation.

6. In an electron tube system the combination of an electron tube having grid, filament and plate electrodes, input and output circuits interconnecting said electrodes, an inductance device included in each of said circuits, the inductance device in said output circuit being connected in a balance circuit, and an impedance in shunt with said inductance device arranged to be variably increased in one of said circuits at the same rate that it is decreased in another of said circuits for variably increasing or decreasing the tendency of said balance circuit to regenerate, whereby said electron tube circuits are maintained constantly in a desired state of regeneration or oscillation.

7. In an electron tube system the combination of an electron tube having grid, filament and plate electrodes, input and output circuits interconnecting said electrodes, an inductance device included in each of said circuits, a balance circuit connected in said output circuit and including in series therewith the inductance device of said output circuit, said last mentioned inductance device being divided into two portions and having means connected across each portion for increasing and decreasing the tendency of said electron tube circuits to regenerate, whereby said electron tube circuits may be maintained constantly in a predetermined state of regeneration or oscillation.

8. In an electron tube system, the combination with an electron tube having grid, filament and plate electrodes, an input circuit including said grid and filament electrodes, an output circuit including said plate and filament electrodes, an inductance device interposed in each of said circuits, the inductance device in said output circuit being arranged in a balance circuit with a midpoint of said last named inductance device connected with said plate electrode thereby dividing said inductance device into two portions, and means for adjusting said balance circuit, whereby one portion of said last named inductance device tends to increase the regenerative condition of said electron tube circuits, while the other portion of said last mentioned inductance device tends to decrease the regenerative properties of said electron tube circuits, whereby a condition of balance may be obtained for maintaining said electron tube circuits constantly in a desired state of regeneration or oscillation.

9. In an electron tube system, the combination with an electron tube having grid,

filament and plate electrodes, an input circuit including said grid and filament electrodes, an output circuit including said plate and filament electrodes, an inductance device interposed in each of said circuits and magnetically associated, the inductance device in said output circuit being arranged in a differential circuit with an intermediate point of said inductance device connected with said plate electrode, thereby dividing said inductance device into two portions having fields of opposite phase, whereby one portion tends to increase the regenerative condition of said electron tube circuits, while the other portion tends to decrease the regenerative properties of said electron tube circuits, and a single means associated with the extremities of said output circuit inductance for adjusting said electron tube circuits to a desired resultant state of regeneration or oscillation which increases the magnetic field set up in one portion of said output circuit inductance inversely as it decreases the magnetic field in the other portion, said differential circuit maintaining said resultant regeneration at a constant value.

10. In an electron tube system, the combination with an electron tube having grid, filament and plate electrodes, an input circuit including said grid and filament electrodes, an output circuit including said plate and filament electrodes, an inductance device interposed in said input circuit, a differentially connected inductance device consisting of two branch circuits interposed in said output circuit and magnetically coupled with said inductance device in said input circuit, and a single means inversely adjusting the field intensity in the two branches of said differentially connected inductance device in said output circuit for securing a desired resultant effect on said input circuit, the differential action of said output inductance device tending to maintain said adjustment at a constant value.

11. In an electron tube system, the combination with an electron tube having grid, filament and plate electrodes, a tuned input circuit including said grid and filament electrodes, an output circuit including said plate and filament electrodes, an inductance device comprising a portion of said tuned input circuit, a differentially connected inductance device consisting of two branch circuits interposed in said output circuit and magnetically coupled with said inductance device in said tuned input circuit, the mutual inductance between said inductance device in said tuned input circuit and said differentially connected inductance in said output circuit remaining constant by reason of fixed physical relationship, and a single regeneration control comprising means of inversely adjusting the field intensity in

the two branches of said differentially connected inductance in said output circuit for securing a desired resultant effect on said tuned input circuit, whereby for a given frequency adjustment of said tuned input circuit the impedance of said output circuit remains essentially constant through the useful range of said regeneration control means, said constant mutual inductance and said constant output circuit impedance tending to maintain a constant frequency for said tuned input circuit against variations in said regenerative control means. 10

In testimony whereof I affix my signature.

EDWIN L. POWELL.
